Primary Examiner — Brett Miller*(74) Attorney, Agent, or Firm* — Carmody Torrance Sandak & Hennessey LLP(57) **CLAIM**

The ornamental design for a canopy, as shown and described.

DESCRIPTION

FIG. 1 is a perspective view of a canopy showing my new design;

FIG. 2 is a top plan view of the canopy design in FIG. 1; FIG. 3 is a first side elevational view of the canopy design in FIG. 1, with the opposite side elevational view being in mirror image;

FIG. 4 is a bottom plan view of the canopy design in FIG. 1;

FIG. 5 is a first end elevational view of the canopy design in FIG. 1, with the second end elevational view being identical;

FIG. 6 is a perspective view of a canopy showing another alternate embodiment of my new design;

FIG. 7 is a top plan view of the canopy design in FIG. 6; FIG. 8 is a first side elevational view of the canopy design in FIG. 6, with the opposite side elevational view being in mirror image;

FIG. 9 is a bottom plan view of the canopy design in FIG. 6; and,

FIG. 10 is a first end elevational view of the canopy design in FIG. 6, with the second end elevational view being identical.

The drawings including symbolic break lines. Any portion of the design between the break lines forms no part of the claim.
